SLUB YARN APPARATUS

John Green Kershaw, Westmount, Quebec, Canada, assignor to Dominion Textile Company Limited, Montreal, Quebec, Canada, a corporation of Quebec, Canada

Application August 8, 1938, Serial No. 223,736
In Canada May 23, 1938

8 Claims. (Cl. 57—38)

This invention relates to apparatus for producing slub yarn.

Yarn of this nature is used for weaving fabric, in which the raised portions, occasioned by the slubs, create a desirable effect. This effect may be altered in many ways by varying the length and spacing of the slubs during the formation of the yarn. In most cases a random effect is sought for so that there will be no semblance of pattern in the fabric. Various mechanisms employed for producing this yarn have embodied means for varying the slub length and spacing, but their scope of operation has generally had limitations preventing their practical application to the production of certain types of slub yarn, particularly that of the "Hymalaya" type, including very long slubs and a very long repeat. Yarn of this type is particularly desirable as it gives a remarkable random effect in the fabric.

One type of slub motion in general use includes a chain provided at intervals with gear segments adapted to speed up the back and middle rolls of spinning frame by engaging a gear connected with them. The chain must move fast enough to be able to impart to these rolls a greater than normal speed, a long repeat thus requiring a considerable length of chain. The same remarks apply in a lesser degree to slub motions employing a clutch operated by a chain having risers actuating the clutch lever. In this case also the chain must move fast so as to close the clutch sharply, to prevent injury to the mechanism or the yarn. Moreover, chain devices are generally inconvenient as compared with those which are gear driven.

There are also cam operated slub motions which are only satisfactory in producing relatively short slubs and relatively short repeats. In these motions the pawl is lifted sharply by engagement with a necessarily fast moving cam element. Consequently, the respective slub lengths are repeated frequently to create the undesirable effect of uniformity. Furthermore, it is impractical to produce on this type of apparatus a yarn having long slubs or a long repeat since the cam must revolve too fast.

It is to the production of the mixed long and short slubs and the long repeat required by the "Hymalaya" type of yarn that the present invention has particular application. Thus, a main object of the invention is to provide means for producing in yarn, slubs varying in length anywhere from a fraction of an inch to several yards and allowing, if necessary, for a very long repeat of several thousand feet.

It is a further object of the invention to furnish positive advantages in simple slub motion for easy attachment to existing spinning frames without change in the latter. It is a further object to provide a motion of this nature which may be used in conjunction with other motions and which may be adapted to operate both sides of the spinning frame. It is a still further object to provide a device of this nature embodying elements permitting of extremely flexible adjustment and control of the slub length so that "Hymalaya" cloth of practically any slub effect may be produced.

With these and other objects in view, the principal features of the invention are embodied in an apparatus employed in conjunction with a spinning frame to increase the speed of the back and middle rolls at intervals, while alternately connecting the back roll drive shaft with an auxiliary slub speed drive. One of these features is a special cam, operating through a pawl and lever to open and close at adjusted intervals a clutch connection between the back roll drive shaft and the slub speed drive. The cam is adapted to move extremely slowly to allow the production of many different slub lengths and spacings without repetition, but at the same time the pawl and peripheral surface of the cam are so constructed and arranged to cooperate in the rapid closing of the clutch to avoid injury to the mechanism or to the yarn by causing an instantaneous speed change. Also, the sharp movement of the pawl independently of the slub speed, permits the production of relatively short slubs, even at the very slow cam speed.

Other features of the invention are also important. For instance, the particular cam includes a number of adjustably mounted segments, the arrangement of which creates the desired peripheral repeat on the cam. The drive of the cam through a reducing gear system from the front roll drive shaft of the spinning frame permits its slow movement, timed to the drafting operation. The nature of the cam and of its drive mechanism permits it to be placed in a position of easy access for adjusting the segments, its face being preferably in a diagonal position so that a pattern disc may be laid adjacent to it to assist in positioning of the segments.

Having thus generally described the nature of the invention particular reference will be made to the accompanying drawings illustrating a preferred mechanical embodiment thereof, and in which:

Figure 1 is a diagrammatic sectional view partly

in elevation through one side of a spinning frame embodying the present invention.

Figure 2 is an end elevation of one side of a spinning frame embodying a slub motion according to the present invention.

Figure 3 is a fragmentary plan view of the spinning frame shown in Figure 2 also illustrating a part of the other side of the spinning frame.

10 Figure 4 is a detailed cross section illustrating the type of the clutch used in the apparatus of Figures 2 and 3.

Figure 5 is a cross section along the line 5—5 of Figure 2.

15 Figure 6 is a diagrammatic view looking in the direction of the front of the cam showing the latter and the pawl and clutch mechanism of the apparatus illustrated in Figures 2 to 5.

20 Figure 7 is an enlarged side elevation of a segment removed from the cam of Figure 6.

Figure 8 is a cross section along the line 8—8 of Figure 6.

25 Figure 9 is a plan view of a setting disc of the type employed to set the segments on the periphery of the cam.

Figure 10 is an enlarged elevation taken in the direction of Figure 6 illustrating particularly the manner of cooperation of the pawl and cam periphery.

30 The spinning frame

Referring particularly to the drawings, A represents a conventional spinning frame including suitably mounted bobbins 11, back rolls 12, intermediate rolls 13, and front rolls 14. It will be understood that only one set of bobbins and one

35 spindle is shown in Figure 1 and that in the remaining figures, with the exception of Figure 3, only one side of the spinning frame is illustrated, which is deemed sufficient for the understanding of one skilled in the art. The back rolls are

40 driven by a back roll drive shaft 15 and the front rolls by a front roll drive shaft 16. The middle roll drive shaft 16a is driven from the back roll

45 drive shaft 15. In the spinning operation, wherein the yarn is drawn out to a smaller diameter, the front rolls 14 normally revolve at a much greater speed than the back and middle rolls 12 and 13, the speed ratio being determined to give

50 the required draft to the yarn. For the production of slub yarn the back and middle rolls are caused, during adjusted intervals, to rotate faster than normal.

The yarn Y passes from the bobbins 11, and 55 is drawn out by first passing between the back rolls 12, between intermediate rolls 13, and then between the much faster moving front rolls 14, and thence it is wound on to spindles 18 by spinning ring travellers. Thus, the spinning operation is accomplished by first drafting and then

60 twisting the yarn.

The front, back, and middle roll drive shafts 15 and 16 and 16a are suitably journaled in the frame A and extend from end to end thereof, in 65 the drawings these shafts being broken away towards the drive end, which, being customary mechanism, is not shown.

The clutch

70 The end of the shaft 16 is provided with a gear 19 adapted to serve as a source of second or slub speed drive for the back roll drive shaft 15 above the gear 19 and meshing with it, mounted on a stub shaft 20 journaled in the frame A, is a gear 21. On the outer end of the stub shaft 20

is a gear 23 which meshes with a gear 22 keyed to the sleeve 24 of a clutch B freely rotatable and laterally slideable on the shaft 16. The clutch sleeve 24 carries an inwardly disposed clutch face 25. A companion clutch face 26 is 5 keyed to the shaft 16 adjacent the face 25, the faces 25 and 26 being normally urged apart, to open the clutch B, by a coil spring 28a. Through the mechanism described, the clutch face 25 is driven from the shaft 16 so that when the clutch 10 B is closed the shaft 15 becomes driven from the shaft 16 at a greater than normal, or slub producing speed, a one-way clutch in the normal drive connections of the shaft 15 permitting it to overrun its normal drafting speed. The speed 15 of the middle roll drive shaft 16a is also increased through its drive connection with the shaft 15.

The mechanism thus described, being of a conventional nature, is easily understood. There 20 will now be described a preferred mechanism for shifting the back and middle rolls from normal to slub speed and vice versa.

Extending diagonally downward from adjacent the front shaft 16, is a shaft 30 on the upper end 25 of which is fixedly mounted a worm wheel 29 driven from the shaft through a worm 27 mounted thereon. The lower end of the shaft 30 carries a worm 31 engaging a worm-wheel 32 mounted on a transversely extending stub shaft 33 30 journaled in a bracket 34 forming a part of the frame A. The stub shaft 33 carries, adjacent its outer end, a gear 35 meshing with a gear 36 mounted on the inner end of a parallel stub shaft 37 also journaled in the bracket 34. 35

The cam

The stub shaft 37 carries on its outer end a bevel pinion 38. This pinion meshes with a bevel gear 39 mounted on a transversely extending 40 shaft 40 supported by the bracket 34. Mounted on the end of the shaft 40, to the back, relatively to the spinning frame, of the bevel gear 39, is a clutch controlling cam C which is a particular feature of the present invention, being adapted to control the closing and opening of the clutch B. From the above description it is seen that the cam C is rotatable from the front roll drive shaft 16.

The cam C is made up of a thick disc-like wheel 50 centrally connected to the end of the shaft 37 by a nut and washer 51, threaded thereto and having on its face inside the periphery an annular T-shaped groove 52. On the wheel 50 are mounted large and small segments 53 and 54 respectively, each segment having a transverse body portion 56 overlying the periphery of the wheel 50, an arm 57 lying adjacent the face of the wheel and a finger 58 engaging an additional slot 61 spaced from the slot 52. These segments are 60 held firmly in place by T-ended bolts 59, passing through orifices in the arms 56 and engaging in the T groove 52, the bolts being threaded into nuts 60.

When the bolts are loosened the segments may 65 be slideably moved about the periphery of the wheel. Each large segment 54 has an arcuate pawl-engaging surface while each small segment 55 has a left or right hand inclined surface 62, all the segments being provided with a bevelled 70 peripheral edge 63.

The segments are arranged on the cam so as to produce a peripheral surface having depressions of varying lengths depending upon the lengths of the slubs which it is desired to pro- 75

duce in the yarn. Relatively short depressions in the peripheral surface are made between the oppositely inclined faces of adjacent oppositely registering small segments 55 while long depressions in the surface are caused by leaving gaps of some length between segments. It is thus evident that various arrangements of the segments in this way permits of a tremendous number of different repeats. A corresponding number of different repeats can thus be produced in the yarn.

The pawl

Controlled by the cam C to close and open the clutch B is a pawl D. This pawl consists of a sleeve portion suitably mounted for free rotation on a pin 81 extending from a bracket 83 bolted to the frame A. This body of the pawl extends from the sleeve 80 downwardly at an angle to terminate in a wedge-shaped tooth 84 adapted to abut the surface of the cam. The tooth 84 includes a face 85 parallel to the inclined segment faces 62 adjacent the direction of travel of the cam as best illustrated in Figure 10, which is particularly important to allow the tooth 84 to move sharply into the depressions in the cam periphery independently of the cam speed. Connected to a bolt 85a extending from the pawl adjacent the tooth 84 is a coil tension spring 86 which extends downwardly and is connected to a bracket 87 extending from the frame A. This spring is adapted to urge the pawl tooth 84 forcibly against the peripheral surface of the cam so as to cause it to enter the cam depressions rapidly. Extending upwardly in the pawl from the sleeve 80 is a lever portion 88 provided with an outwardly extending bolt 89 carrying an adjustable nut 90 adapted to abut the end of a clutch actuator lever E.

The clutch actuator

The lever E comprises a sleeve portion 100 journaled on a diagonally extending shaft 101 mounted on a bracket 102 extending from the frame A. From the lower end of the lever E and adapted to abut the pawl D there projects downwards a nut 104 for contact with the pawl nut 90. Extending upwardly from the sleeve portion 100 is a yoke 107 engaging the sleeve 24 of the clutch B. In order that the lever E may also be adapted for actuation by an auxiliary cam mechanism, it is provided adjacent its lower end with a diagonally extending arm 105 having a knife edge 106, adapted to engage the element of an additional cam H. This arrangement is particularly convenient for use in connection with an auxiliary relatively high speed cam for producing small slubs within the spaces between the long slubs created by the action of the cam C. From the foregoing description it is seen that both the moveable face 21 of the clutch B and the cam C, are gear driven from the front roll drive shaft 16. Cooperating with the cam to close the clutch B at intervals is the pawl D and the clutch lever E. Hence, a continuous operative cycle is provided by a positive gear drive from the front roll drive shaft 16.

The linkage between clutches

As already stated, it is an object of the present invention to provide means operated by one slub motion for connecting the back and middle roll drive shafts of both sides of the spinning frame with a slub speed drive. This means is best illustrated in Figure 3, wherein 120 represents the

back roll drive shaft of the opposite side F of the spinning frame from that already described. On the end of this drive shaft is keyed the inwardly-disposed face 121 of a clutch C. Inside the face 121 on the shaft 120 is mounted a freely 5 rotatable and axially slideable sleeve 122, carrying the other clutch face 123, to which is secured a gear 125 driven as in the other side of the spinning frame from the front roll drive shaft so that the clutch face 123 is driven at a slub 10 producing speed. The faces 121 and 123 are normally urged apart by a coil spring 120a.

A horizontally rotatable rocker arm 130 connects the axially moveable faces 25 and 123 of the clutches B and G respectively. The arm 130 is pivotally mounted on a vertical shaft 131 extending upwards from a bracket 132 in the spinning frame, being held thereon by a nut 133. The arm 130 is provided at each end with yokes 134 engaging the sleeves of the respective clutch faces 25 and 123.

By this linkage an inward movement of the clutch face 25, closing the clutch B, causes a corresponding outward movement of the clutch face 123, closing the clutch G. Thus, the cam mechanism C operates to shift simultaneously the back roll drive shaft of both sides of the spinning frame from normal to slub speed or vice versa.

The operation

Having thus described the structure of the spinning frame and the auxiliary slub producing apparatus, the operation of this mechanism will now be referred to briefly. The periphery of the cam C is first set, as described, by the adjustment of its various component segments 53 and 54 to present a peripheral surface of the desired conformation. To assist the arrangement of the segments, a disc 140, as illustrated in Figure 9, may be laid alongside the cam face. Since a very small portion of the cam periphery may represent a relatively long slub, this adjustment must be accurate to produce the effect desired without variation.

When the spinning frame is set in motion, the front and back roll drive shafts 16 and 15 take up their normal speeds as usual, from the drive of the frame, which is located at the end opposite to that illustrated. The front roll drive shaft 16 operates through the train of gears 19, 23 and 22, to rotate the clutch face 21. The shaft 16 also operates through the worm 28, the worm wheel 29, the worm 31, the worm wheel 32, the gear 35, the gear 36, the bevel pinion 38 and the bevel gear 39, to rotate the cam C at a very low speed which, of course, may be adjusted by changing the size or nature of the gears in the train. As this cam is rotated the pawl tooth 84 is held on the peripheral surface of the segments until it reaches the top edge of a sloping face 62 of one of the small segments, at which point it is released and snaps down sharply into the depression under the urge of the spring 86, the face 62 of the segment forming a slide for the parallel face 86 of the pawl. It is important to note that the speed at which the pawl drops into the cam depression is quite independent of the speed at which the cam is rotating, thus permitting a very slow cam speed without reducing in any way the efficiency of the clutch closing action. As the pawl tooth drops into the depression of the cam periphery, the upper portion 88 is forced outwardly against the clutch lever E, which is also forced outwardly, forcing inwardly the upper end of the clutch lever carrying the yoke 107. 70 75

This forces the slidable clutch face 25 quickly into engagement with its companion clutch face 26 closing the clutch B and causing the shaft 15 to rotate at the speed of the clutch face 26, or in other words at slub producing speed. Through the linkage of the rocker arm 130 the clutch G is also closed and the shaft 129 caused to rotate at slub speed through gearing already described.

As the cam C continues to rotate the pawl tooth 84 rides along a gap between the segments. If it is a long depression, the tooth 84 rides on the outer periphery of the wheel 50 between segments, before it is lifted by the sloping face of a small segment, or, if it is a short depression, the sloping face of the small segment starts immediately to lift the tooth 84 from the depression to the surface of the segments moving the upper portion 88 in an inward direction and allowing the upper end of the clutch lever E to move outwards under the urge of the spring 20a causing the clutch faces to part.

The action of the pawl in and out of the depressions is continued according to the disposal of the segments on the cam periphery and the clutch is opened and closed accordingly, the closing of the clutch always occurring instantaneously as the pawl is released by the segments, the opening of the clutch always being caused as the pawl is lifted by an inclined segment surface. As a result, slubs of varying lengths, bearing a direct ratio to the length of respective depressions on the cam are produced. The length of the slubs and of the intervals between them may be thus calculated in advance and the periphery of the cam adjusted by arrangement of the segments to produce any desired sequence of slubs.

Advantages summarized

40 The following summarized advantages and the many others possible by the use of this mechanism will become obvious to those skilled in the art.

(1) The mechanism is entirely gear operated, 45 thus enjoying the advantages associated with devices of this nature, and lacking the disadvantages of chain operated mechanisms.

(2) The cam may be easily and accurately adjusted to give the desired effect owing to the 50 manner of its construction; its position permits easy access for the operator, and the use of a standard pattern disc to assist his arrangement of the segments.

(3) The motion may thus be used to produce 55 slub yarn having slubs of practically any desired length, and an extremely large number of different combinations without repetition of the repeat.

(4) The mechanism is extremely compact, 60 making it practical to operate a number of frames in the production of "Himalaya" yarn, where it would be impractical to use a number of the chain mechanism, owing to the cumbersome lengths of chain required.

(5) The cam may be operated at a very slow 65 speed to produce a long repeat since the clutching speed is independent of the cam speed, the spring-operated pawl being pulled down sharply from the surface of the segments into each cam depression, to avoid injury to the mechanism or to the yarn. In apparatus in which the clutching speed is dependent on the cam speed the cam or chain must move fast enough to avoid injury to the mechanism or to the yarn to obtain fast clutching, which distinctly limits the capabilities

of the apparatus with regard to length of slub and length of repeat.

Practical example

In order to further demonstrate the operation and advantages of a cam constructed according to the present invention, an example from actual practice will now be given.

A slub motion of the following dimensions was applied to a spinning frame:

Slubbing cam..... inches diameter 12
Slubbing cam including segments..... do 12%
Front roll..... do 1

The frame and the elements of the slub were adjusted to operate as follows:

Front roll..... revolutions per minute 77
Yarn delivered..... inches per minute 241.78
Slubbing cam, peripheral speed..... do 1.89
Slubbing cam, time for one revolution 20
minutes 19.93

With these characteristics of structure and operation, the following ratios were obtained:

The slubbing cam was required to travel .0078" to produce 1" of slub.

A yarn was produced in which the length of the repeat was 4687.6" and in which characteristic lengths of slubs in the cloth and ground yarn in between slubs, were as follows.

Slub	57"	average count	7s	30
Yarn	500"	average count	20s	
Slub	3"	average count	7s	
Yarn	625"	average count	20s	
Slub	64"	average count	7s	35
Yarn	855"	average count	20s	
Slub	30.6"	average count	7s	
Yarn	546"	average count	20s	
Slub	52"	average count	7s	40
Yarn	546"	average count	20s	
Slub	3"	average count	7s	
Yarn	703"	average count	20s	
Slub	57"	average count	7s	
Yarn	393"	average count	20s	45
Slub	3"	average count	7s	
Yarn	250"	average count	20s	

4687.6"

In this particular example the long slubs produced by the cam were interspersed by short slubs produced by another motion. However, it is obvious that by adjusting the lengths of the depressions between segments very short slubs could also be produced by the cam mechanism of the present invention despite its slow speed. 55 A quick inward motion of the clutch is made possible by the urge of the spring upon the pawl.

It is not wished that this example be considered in a limiting sense but merely to add quantitative data to the qualitative description already furnished.

I claim:

1. A slub yarn producing attachment for spinning frames having a back roll and a front roll, a back roll drive shaft and a front roll drive shaft, normal drafting speed drive connection for said shafts, a slub speed drive connection for said back roll drive shaft, a clutch for engaging said slub speed drive connection, a spring urging said clutch from engagement with said slub speed drive connection, a clutch lever for actuating said clutch, a rotatable cam for controlling the operation of said clutch, a pawl operatively intervening said cam and said clutch lever, means urging said pawl to move said clutch into en- 75

gaged position, elements on said cam to retain said pawl and clutch in disengaged position, said elements being selectively disposed to form therebetween spaces adapted to free said pawl to 5 permit its release to close said clutch at selected intervals, said elements having inclined faces adapted to return said pawl to clutch disengaged position, a speed reducing drive connection between said front roll drive shaft and said cam for rotating said cam at a low speed.

10 2. A slub yarn producing attachment for spinning frames as claimed in claim 1 wherein certain of said elements include inclined faces at the entry of said spaces, and said pawl includes a face parallel to said last-mentioned inclined faces and adapted to slide thereupon during its clutch engaging stroke.

15 3. In an apparatus of the nature described, a rotatable cam disc, a plurality of elements mounted on said disc to form a continuous elongated cam surface, gaps of selected length between said elements at selected intervals, clutch actuator means normally held between said elements to retain the clutch in disengaged position including a cam-engaging pawl, means for moving said cam surface relatively to said pawl, said clutch actuator means being normally held by said elements to retain the clutch in disengaged position, means acting independently of 20 said cam on said actuator means, said gaps adapted to release said actuator means for movement of the clutch into engaged position.

25 4. In an apparatus of the nature described, a cam disc, an annular T-groove in the face of said disc and spaced from the periphery thereof, a plurality of elements adjustably mounted on said disc to form a working peripheral surface, each of said elements having an arm overlying the periphery of the disc and a shank overlying the face thereof, a T-bolt connected to each element and engaging in said groove, a clutch actuator member engaging the working surface of said cam to control the movement of a clutch, means urging said clutch actuator member 30 against said working surface, said elements forming a plurality of selectively spaced apart indentations of adjustable length.

35 5. In an apparatus of the nature described, a cam disc, a plurality of elements adjustably mounted on said cam disc to form a working surface thereon, each of said elements having an arm overlying the peripheral surface of the disc and a shank overlying the face thereof, means for retaining said elements on said disc, certain 40 adjacent segments having inclined faces forming therebetween indentations, a clutch actuator pawl urged against said working surface said pawl having a working surface parallel to the inclined segment faces forming the entry side 45 of the indentations, and means for rotating said cam disc.

6. A slub yarn producing attachment for spinning frames having a back roll and a front roll,

a back roll drive shaft and a front roll drive shaft, normal drafting speed drive connection for said shafts, a slub speed drive connection for said back roll drive shaft, a clutch for engaging said slub speed drive connection, a cam shaft, 5 rotatable cam means mounted on said cam shaft, said cam means having an elongated cam surface, a connecting shaft extending from adjacent said cam shaft to adjacent said front roll drive shaft, a worm of said connecting shaft, a gear connection between said cam shaft and said worm, a worm of said front roll drive shaft, a gear connection between said drive shaft worm and said connecting shaft, clutch actuator means normally held by said cam to retain the 10 clutch in disengaged position, means acting independently of said cam to urge said actuator means to move the clutch into engaged position, said cam being adapted to release and engage 15 said actuator means at selected intervals to cause engagement and disengagement of said clutch.

20 7. A slub yarn producing attachment for a spinning frame having front and back rolls on each side thereof, front and back roll drive shafts for said front and back rolls, a normal drafting speed connection for said front and back roll drive shafts, a supplemental different slub speed drive connection for each back roll drive shaft, a clutch on one back roll drive shaft having an outer element moveable inwardly to engage a 25 slub speed drive connection, a clutch on the other back roll drive shaft having an inner element moveable outwardly to engage a slub speed connection, rotatable cam means having a connection with said outer element, elements associated with said cam means adapted to selectively and intermittently move said outer element into engaged or disengaged position, linkage between said outer and inner elements whereby a 30 movement of said outer element causes a corresponding movement of said inner element.

35 8. An apparatus for producing slub yarn for spinning frames having a back roll and a front roll, a back roll drive shaft and a front roll drive shaft, normal drafting speed drive connection 45 for said shafts, a slub speed drive connection for said back roll drive shaft, a clutch for engaging said slub speed drive connection, a clutch actuator member, a clutch closing member normally urged to move said actuator lever into clutch 50 engaged position, slowly moveable cam means for retaining said clutch closing member in clutch open position and for retaining said clutch closing member to clutch closed position, means for rotating said cam means at a very slow speed 55 to permit long intervals between the movements of said clutch, a clutch closing lever, an element on said lever for engagement by supplementary cam means operable when said lever is in said clutch open position to permit clutch closing 60 movements intermediate those occasioned by said cam.

JOHN GREEN KERSHAW.
